PREFABRICATED WALL FORM

Arti Arrighini, Detroit, and George A. Van Sickle,
Mount Clemens, Mich.

Application March 29, 1948, Serial No. 17,644

6 Claims. (Cl. 25—131)

1

This invention relates generally to prefabricated forms and refers more particularly to forms of the type employed for fashioning composition walls.

One of the objects of this invention is to provide a collapsible wall form composed of a relatively few simple parts capable of being readily erected and disassembled with a minimum amount of labor.

Another object of this invention is to provide a prefabricated form wherein the relatively few simple sections are releasably secured in assembled relationship by devices which are exceedingly simple to manipulate and which cooperate to securely hold the sections in proper relationship during pouring or introduction of the composition material therebetween.

The foregoing as well as other objects will be made more apparent as this description proceeds, especially when considered in connection with the accompanying drawings, wherein:

Figure 1 is a fragmentary perspective view of a prefabricated wall form embodying the features of this invention;

Figure 2 is a fragmentary perspective view of a part of the form shown in Figure 1;

Figure 3 is a sectional view taken on the line 3—3 of Figure 1;

Figure 4 is a sectional view through one of the releasable holding devices provided;

Figures 5 and 6 are sectional views taken respectively on the lines 5—5 and 6—6 of Figure 4.

A part of a prefabricated wall form embodying the features of this invention is shown in Figure 1 as comprising a base unit 10 and a vertical wall forming unit 11 supported on the base unit. The base unit 10 comprises laterally spaced rails 12 adapted to rest on a suitable foundation, and designed to cooperate with one another to provide a confined space in which a footing 13 for a vertical composition wall 14 may be formed. The base unit 10 forms no part of the present invention, and as a consequence, is not described in detail herein. It will suffice to point out that the rails 12 of the base unit may be extruded from aluminum or some similar material to the general cross section indicated in Figure 3 of the drawings, and have provision for supporting the vertical wall forming unit 11.

The wall forming unit 11 comprises laterally spaced vertical walls 15 respectively supported at the bottom edges on the rails 12 and cooperating with one another to provide the space therebetween required to form the vertical composition wall 14. Each vertical wall 15 in turn comprises

2

a plurality of vertical sections 16 separable from one another, and adapted to be releasably secured together in edge to edge relationship by suitable clamps 17 to be more fully hereinafter described.

Each wall section 16 comprises a frame 18 and a panel 19 suitably secured to the inner surface of the frame 18. The frame 18 for each section 16 is composed of top, bottom and side members 20, 21 and 22 respectively. In cases where the wall sections 16 are of substantial width, it is also preferred to reinforce the same with an upright member 23 positioned intermediate the opposite side members 22. In any event the opposite side members 22 of each wall section 16 are connected adjacent the upper end of the wall section by a pair of laterally spaced strips 24, and are also connected at the bottom by a similar pair of laterally spaced strips 25. These strips are shown in Figure 2 of the drawings as being generally L-shaped in cross section, and are secured to the upright members of the frame 18 with the horizontal flanges 26 extending laterally inwardly and positioned adjacent one another. It will be understood that the upright members of the frame are suitably notched to receive the horizontal flanges 26.

The above construction is such that when the wall sections 16 are positioned in edge to edge relationship on the supporting unit 10, the panels 19 of the several sections cooperate to form a continuous substantially uninterrupted surface against which the composition wall may be cast. In this connection it will be noted that the laterally spaced rails 12 of the base unit are formed with upwardly opening channels 26' of sufficient dimension to freely receive the lower end portions of the wall sections 16 and thereby position the latter in proper relationship. Attention is further called to the fact that when the several sections 16 of the laterally spaced walls 15 are respectively positioned on the rails 12 of the base unit, the strips 24 on adjacent sections assume positions in alignment with one another and the strips 25 on adjacent sections also assume positions in alignment with one another.

The opposed sections 16 of the vertical walls 15 are held in proper laterally spaced relationship by vertically spaced ties 27 comprising transverse bars 28 and clips 29. As shown particularly in Figure 3 of the drawings, the bars 28 extend through aligned openings 30 formed in the opposed wall sections 16, and the opposite ends of the bars respectively project between the pairs of strips 24 and 25. It will be noted that the bars 28 taper in width and in thickness from a point

adjacent one end to the opposite end. This construction enables readily removing the bars from the composition wall 14 after the latter has become set sufficiently to enable disassembling the form. The opposite end of each bar is formed with an elongated slot 31 of sufficient dimension to receive one of the clips 29. The openings 31 are spaced laterally beyond the transverse strips 24 and 25, so that the clips abut the outer surfaces of the strips and thereby hold the opposed wall sections 16 against relative movement in an outward direction. Formed on or secured to the upper end of each clip 29 is a hook 32. The hooks 32 on the upper ends of the clips are adapted to respectively hook over the uppermost strip in each pair of strips 24 and 25 in the manner clearly shown in Figures 2 and 3 of the drawings. Thus the hooks 32 cooperate to hold the opposed wall sections 16 against relative shifting movement in an inward direction.

As stated above the adjacent vertical edge portions of the wall sections 16 are secured together by the clamps 17. As shown particularly in Figures 2, 4 to 6 inclusive, each clamp 17 comprises a pair of relatively slidable parts 33 and 34. The part 34 comprises a laterally inwardly opening U-shaped member having oppositely extending support engaging flanges 35 and having a laterally inwardly extending finger 36 at one end. The part 33 is in the form of a plate which is slidably supported in the U-shaped member 34 and is held in assembled relation with the U-shaped member by a strip 37 which is welded or otherwise suitably secured to the U-shaped member at the open side thereof. The end of the part 33 opposite the end of the part 34 having the finger 36 thereon is also formed with a laterally inwardly extending finger 38. As shown particularly in Figure 4 of the drawings, the fingers 36 and 38 converge to provide, in effect, hook portions for respective engagement with pins 39. The pins 39 are respectively secured to adjacent wall sections 16, and in the present instance, are carried by the respective pairs of strips 24 and 25.

In the present instance a pair of clamps 17 is provided for securing adjacent wall sections 16 in edge to edge relationship, and these clamps are respectively positioned opposite the strips 24 and 25, as shown in Figure 1 of the drawings. In detail each clamp is positioned so that the flanges 35 on the U-shaped part 34 bear against the outer sides of the adjacent ends of the strips in overlapping relationship to the joint between the vertical edges of adjacent wall sections. In positioning the clamps the fingers 36 and 38 are respectively engaged with the pins 39 in the manner shown in Figure 4 of the drawings, so that relative sliding movement of the parts 33 and 34 in a direction toward one another urges the adjacent vertical edges of the wall sections in intimate contacting relationship.

The clamp parts are relatively moved toward one another by a stake 40 which extends through vertical slots 41 formed in the clamp parts 33 and 34. The location of the slots 41 in the respective clamp parts is determined so that the slots register with one another in the clamped position of the parts, and the stake 40 is wedge-shaped to impart a cam action on opposite end walls of the slots 41 to effect alignment of the slots in response to movement of the wedge-shaped stake in a downward direction relative to the clamp parts. In other words the construction is such that as the wedge-shaped stake is

moved downwardly through the slots 41, the parts 33 and 34 of the clamp are relatively moved in a direction toward one another. As the clamp parts are relatively moved toward one another, the inclined edges on the fingers 36 and 38 respectively exert a camming action on the pins 39 to force the vertical edges of adjacent wall sections together.

It of course follows from the above that the clamps may be readily released by merely moving the wedge-shaped stakes 40 in an upward direction to release the clamping action on the respective wall sections. After the stake 40 has been raised a relatively short distance, the clamping parts may be relatively moved in directions away from each other a sufficient distance to disengage the fingers from the respective pins 39, whereupon the clamp may be removed from the wall sections. If desired the lower end of each stake 40 may be provided with a pin 42 which limits the extent of withdrawal of the stake, and retains the latter in assembled relationship with the clamp.

It follows from the foregoing that the several wall sections may be readily positioned in proper relationship by the supporting base unit 10, and that adjacent vertical edges of the wall sections may be quickly secured together by the clamps 17. These clamps are of a nature which enable the same to be readily manipulated to either clamp the wall sections together or to release the same. It will further be noted that the construction of the tie rods described at some length above renders it possible to install and remove these rods in a very short period of time. Thus the tie rod arrangement and the clamp construction cooperate to permit assembling and disassembling a wall form of substantial size in a relatively short space of time, and with a minimum amount of labor.

What we claim as our invention is:

1. A collapsible form for composition walls, comprising wall sections adapted to be supported in edge to edge relationship, a pair of laterally spaced strips secured to the outer sides of each wall section and positioned so that the strips of one pair are substantially aligned with the strips of the other pair in the assembled relation of the wall sections, a pair of pins respectively supported between the pairs of strips at opposite sides of the joint between the wall sections, a clamp having parts slidably engageable with one another and adapted to be positioned for relative sliding movement transversely of the joint between the wall sections, means for relatively sliding the parts in directions toward one another, and fingers respectively projecting inwardly from said parts between the parts of strips and responsive to relative movement of the parts toward one another to clamp adjacent edges of the wall sections together.

2. A collapsible form for composition walls, comprising wall sections adapted to be supported in edge to edge relationship and laterally spaced from similar opposing wall sections, tie members extending through aligned openings in said opposing wall sections, laterally spaced strips extending transversely of each section on opposite sides of said openings and tie members, anchorage clips respectively extending through slots formed in opposite ends of said tie members beyond the strips for abutting engagement with the outer sides of the strips, clamping elements respectively fixed to adjacent sections at opposite sides of the joint therebetween, a clamp abutting said strips

in overlapping relationship to the joint and having parts supported for relative sliding movement transversely of said joint, said parts including fingers respectively engageable with said clamping elements upon relative sliding movement of the parts toward one another to hold adjacent edges of the sections in engagement, and means for relatively sliding the parts toward one another and for releasably holding said parts in their respective clamped positions.

3. A collapsible form as defined in claim 2, wherein the tie member is tapered from a point adjacent one end to the opposite end to permit ready withdrawal of said member from the composition material between the opposed wall sections.

4. A collapsible form as defined in claim 2, wherein the anchorage clips are provided with hook-like portions at the upper ends to extend laterally inwardly over the top edge of one of said strips to engage the inner side thereof.

5. A collapsible form for composition walls, comprising wall sections adapted to be supported in edge to edge relationship, laterally spaced strips extending transversely of each section and positioned so that the strips on adjoining sections are in substantial alignment with each other when said sections are in assembled relation, clamping elements supported between said strips on opposite sides of the joint between the sections, means for securing the sections together including a clamp abutting said strips and having parts supported for relative sliding movement transversely of the joint and having fingers respectively engageable with said elements upon relative sliding movement of the parts toward one another to hold adjacent edges of the sections in engagement, and releasable means for actuating said clamp and holding the parts in their respective clamped positions.

40

6. A collapsible form for composition walls, comprising wall sections adapted to be supported in edge to edge relationship, laterally spaced strips extending transversely of each section and positioned so that the strips on adjoining sections are in substantial alignment with each other when said sections are in assembled relation, clamping elements supported between said strips on opposite sides of the joint between the sections, means for securing the sections together including a clamp abutting said strips and having parts slidably engageable with one another and adapted to be positioned for relative sliding movement transversely of the joint between the sections, fingers projecting inwardly from the respective parts and respectively engageable with the outer sides of the clamping elements for urging adjacent edges of the wall sections in contact, and an element extending perpendicular to the direction of relative sliding movement of the parts through registering openings in said parts and tapered to relatively move the parts in directions toward one another in response to movement thereof in one direction.
